CLAIM

The ornamental design for a cover for transport climate control unit, as shown and described.

DESCRIPTION

FIG. 1 is a front perspective view of a cover for a transport climate control unit showing our new design;

FIG. 2 is a front planar view thereof;

FIG. 3 is a left side planar view thereof;

FIG. 4 is a right side planar view thereof;

FIG. 5 is a top planar view thereof; and,

FIG. 6 is a bottom planar view thereof.

In the drawings, the broken lines show elements of the article that form no part of the claimed design.
